UNITED STATES PATENT OFFICE.

WILLIAM E. PHILIPS, OF CLEVELAND, OHIO, ASSIGNOR TO THE STEARNS' CONVEYOR COMPANY, OF CLEVELAND, OHIO, A CORPORATION OF OHIO.

PIVOTED BUCKET CONVEYER.

Application filed April 13, 1921. Serial No. 460,929.

To all whom it may concern:

Be it known that I, WILLIAM E. PHILIPS, a citizen of the United States, residing at Cleveland, in the county of Cuyahoga and State of Ohio, have invented a certain new and useful Improvement in Pivoted Bucket Conveyers, of which the following is a full, clear, and exact description, reference being had to the accompanying drawings.

10 This invention relates to conveyers and particularly to conveyers of the type wherein dumping buckets are employed.

One of the objects of the invention is to provide in a bucket conveyer, a simple form 15 of bucket and an efficient means for dumping it.

A further object of the invention is to provide in a conveyer a bucket which is adapted to turn completely over with a 20 continuous motion to dump its contents.

An additional object of the invention is to provide in combination a bucket, means to gradually invert the bucket, without undue shock or jar and then return it to normal 25 position.

Another object of the invention is to provide in combination with a dumping bucket, conveyer means to cause the buckets to dump 30 their contents at spaced points along the trackway.

Still another object of the invention is to provide an efficient trip carriage for dumping the bucket of the conveyer, together with effective means for moving this carriage.

35 Further objects of the invention will be apparent from the following description taken in connection with the accompanying drawings, wherein Fig. 1 is an elevation of a portion of a conveyer constructed according to my invention; Fig. 2 is a transverse vertical section of the same; Fig. 3 is a top plan view of the portions of the conveyer shown in Fig. 1; Fig. 4 is a sectional elevation of a trip carriage looking from the interior outwardly; Fig. 5 is a longitudinal sectional elevation of a pair of adjacent conveyer rollers and associated part; Fig. 6 is a sectional plan of the same; Fig. 7 is an elevation of a conveyer structure; Fig. 8 is a top plan view partly in section, showing the means for reversing the travel of the trip carriage, and Fig. 9 is an elevation of the clutch and sheave.

Referring to the drawings by reference characters, I have shown at 5 a conveyer comprising a series of connected members passing over suitable sprockets 6, mounted in standards 7, a portion of a conveyer is shown in detail in Fig. 1, wherein 10 is a suitable supporting bracket having a base 55 portion 11, a transverse lower member 12, and spaced upper flanges 14. I have shown suitable tracks, as T-rails 15, secured to the cross member 12, while upon the upper portion 14, I may provide suitable rails 18. 60 These rails may be secured to the brackets in any suitable manner, as by clamps 19.

The conveyer mechanism is adapted to move on wheels 20 shown as running on the rails 18. These wheels are shown as 70 mounted on suitable axles 21. Upon the axles I may secure links 23 joined to form a belt-like structure. The links 23 may be secured in place by suitable means such as 75 cotterpins 24.

The conveyer 23 is adapted to have buckets as shown at A mounted thereon. These buckets may all be of similar construction comprising curved bottom and side portions 36 and the end portions 27, 80 shown as substantially flat. I have indicated reinforcing members at 28 which may be castings secured by riveting or bolting, or any other suitable manner upon the ends of the buckets. Each reinforcement is shown 85 as provided with a boss 30 through which the axle 31, upon which the bucket rotates, extends.

The axle 31 is continued through both sides of the links 23, as at 31^a. A suitable 90 spacing member 31^b through which the axle extends has bosses 31^c fitting notches in the links 23 to prevent rotation thereof. Lateral movement is prevented by the stud 31^d.

The reinforcement 28 is also shown as 95 provided with a pair of upper bosses 32 and 33, and a lower boss 34. The upper bosses are of less length than the lower boss, and through these upper bosses shafts 35 extend. Upon these shafts I mount suitable anti-friction rollers 37. The shaft 35 may include a fastening means, such as the nut 38, and may have a collar at its outer end to secure the roller in place while the inner end may be stepped, as at 39, to provide a 100 shoulder to bear upon the boss so that the 105

nut 38 may be tightened without preventing rotation of the roller. The lower boss 34 is fitted in a similar manner with a roller 40:

- 5 A suitable trip carriage 50 is shown as mounted on wheels 51 which are adapted to run on the lower track 15. This carriage 50 is provided at opposite sides with outer and inner cam surfaces, the outer cam surface being designated 53, while the inner surface is designated 54. The outer cam surface is shown in Fig. 1, as comprising upwardly inclined portions 55 which merge into the straight portion 56.
- 10 15 The inner cam comprises the upwardly inclined end portions 57 connected to the straight portion 56. Above the inclined portions 57, I have indicated approximately triangularly shaped cam portions 58. The 20 two portions 57 and 58 between them provide in effect a groove 59 for a purpose to be presently described.

The action of the trip carriage on the dumping buckets will now be described. 25 for convenience, we will assume that the trip carriage is stationary, the belt 23 is moving to the left in Fig. 1, and that the bucket A, is just in the act of being dumped. The lower roller 40 on this bucket A strikes the 30 outer cam and begins to run up the inclined portion of the same as the bucket is advanced along the rail. As the bucket nears the straight portion 56 of the rail, its top approaches the vertical as it turns about the 35 pivot 30. As its bottom roller 40 moves on to the straight portion of the rail, the roller on the boss 32 strikes the inclined portion 57 of the inner cam and as the bucket advances this roller moves between the cams 57 and 40 58, consequently its movement is upward thus causing the bucket to be inverted.

The continued movement of the bucket causes the forward roller on the boss 32 to move through the groove 59 between the 45 cams 57 and 58 at the left as shown in Fig. 1. As soon as this forward roller leaves the groove 59, the roller 34 comes in contact with the outer cam surface 55 and moves down the incline to gradually right the 50 bucket.

It will be apparent that the operation of 55 turning the bucket over will be done without any jar or shock detrimental to the operating parts of the structure. It is exceedingly simple, while positive in operation.

Instead of having the buckets dump in one place it is frequently desired to cause 60 them to dump in order over an extended length. In order to provide such a dumping action, I have shown a device in Figs. 7, 8 and 9 wherein the trip carriage 50 is connected at each end with cables 83, shown as wound on sheaves 85 and 86 mounted on shafts 87 and 88. The sheaves are free to 65 rotate on the shafts and in order to drive

them I provide suitable means comprising clutch members 89 and 90. These clutches comprise the usual toothed discs 94 and 95, levers 96 and 97 and operating members 98 and 99 on the lever. The action is such that the movement of each operating member 98 and 99 back and forth causes the clutches to be thrown in and out.

The cables 83 secured to the trip carriage 50 and wound upon the sheaves 85, carry 75 suitable stop members 100. These stops may include suitable springs 105, and may be made adjustable lengthwise of the cables 83 by the adjustable means 106, shown as a sliding collar.

To prevent undue shock, the cables 83 are secured to each end of the trip carriage by suitable spring connections 110. These connections may comprise the rod 111 having a spring 112 thereon, bearing at one end 85 against the trip carriage and at the other end against a suitable stop or abutment 114 on the rods 111.

It is to be noted that the stop members 100 are secured on the cables near the point 90 of attachment of the cable to the trip carriage 50. Near the other end of the cables I may provide suitable stop members 120, here shown as tubular members surrounding the cable and secured thereto. These 95 stop members 100 and 120 are adapted to operate on opposite sides of the operating member 98. The stop member 100 serving to throw out the clutch connected with an operating handle while the member 120 100 throws in the clutch. The member 120 may be of elastic or resilient material such as a rubber hose or tube.

The operation of the device will be described. The trip carriage 50 is shown as 105 moving toward the left in Fig. 5. A further movement will cause the stop 100 to strike the operating member 98 and thus throw out the clutch 89. At the same time the bumper 120 on the other cable strikes the 110 other operating member 99 and throws in the clutch 95. This causes the cable to move in a reverse direction and to wind up on the sheave 87 while unwinding from the sheave 85. The movement of the trip carriage, it 115 will thus be seen, is alternately back and forth. The conveyer buckets move in one direction and since the trip carriage has reverse movement first with and then opposite to the movement of the conveyer buckets, it follows that in order to obtain definite spaced points of dumping the diameter of the sheaves of the two pulleys must differ. Consequently the sheave 85 is shown as of greater diameter than the sheave 87.

It will be apparent that I have described a device whereby the buckets may be dumped in order over an extended space, and in which the operating means works automatically.

It will, of course, be understood that, if desired, the trip carriage 50 can be arranged to dump repeatedly at the same place.

Having thus described my invention, I 5 claim:

1. A trip carriage for endless conveyers comprising in combination, two connected frame members, and wheels supporting said members, each of said members having an 10 inner and an outer trackway.
2. In combination, an endless chain comprising a plurality of pivoted buckets, rollers carried by each bucket, a trip carriage disposed beneath the conveyer, said carriage 15 having outer cam surfaces and inner cam surfaces providing trackways for the rollers, the inner trackways being disposed in a vertical plane different from that in which the outer trackways are disposed.
- 20 3. In an endless bucket conveyer, supports, sprockets journaled in the supports, sheaves mounted co-axial with said sprockets, a trip carriage adapted to dump said buckets, a

cable connected to said sheaves and trip carriage, a clutch connecting each sheave with a 25 source of power, and means adjacent said trip carriage to cause it to throw the clutch in and out.

4. A link in a conveying mechanism comprising a pair of opposed link members, a 30 pair of axles joining the ends of said link members, wheels rotatably mounted on the axles, a dumping bucket pivotally mounted intermediate the rails, said bucket having a 35 triangular reinforcement at each end, a plurality of rollers arranged on said reinforcement, said rollers being adapted to first invert and then right the bucket, said last mentioned means comprising a trip carriage, the trip carriage including a member having 40 an inner and an outer trackway at either side, upon which said rollers may engage.

In testimony whereof, I hereunto affix my signature.

WILLIAM E. PHILIPS.
